ELECTRICAL SWITCH

Herbert J. Crabbs, Wilkinsburg, Pa., assignor to
 Westinghouse Electric & Manufacturing Company, East Pittsburgh, Pa., a corporation of Pennsylvania

Application April 20, 1939, Serial No. 268,906

23 Claims. (Cl. 200—162)

The invention relates to electrical switches in general, and more particularly to switches designed for high current carrying capacity and employed in moderate and high-voltage electrical transmission or distribution systems and to methods of forming the contact elements.

In switches of the above-mentioned type, it has been found desirable to provide the blades with raised contact portions to restrict the contact area at both ends of the switch. This construction, together with the usual spring cup washers, provides a relatively high contact pressure per unit of contact area, making an efficient electrical joint.

In this type of construction, as well as in other types even where restricted contact area is not provided, considerable difficulty has been experienced in making the blade contact portions contact properly with the tongues. It is apparent that to prevent any localized points of contact and to show uniform abrasion or marking on the tongues, the blades and tongues must be perfectly true and perfectly lined up with each other. This is entirely impractical from a manufacturing standpoint, as no matter how carefully machined, the edges of the tongues seem to be higher than the central surface. This may be only on the order of a fraction of a thousandth of an inch, yet it is enough to produce localized points of contact and a poorly marked contact.

Some trouble has also been experienced with galling of the contact portions, particularly at the hinge end of the switch. This results from the entry of abrasive dirt or material between the contacting portions.

An object of the present invention is the provision of an improved electrical switch which provides proper and uniform contact between the blades and tongues and uniform marking of the contacts, even though the parts are not specially trued and perfectly aligned.

Another object of the invention is the provision of an electrical switch of improved construction which provides uniform restricted area contact and uniform contact marking.

Another object of the invention is the provision of an electrical switch having an improved construction which provides uniform limited area contacts and uniform contact marking without requiring any special machining, truing and aligning of the parts.

Another object of the invention is the provision of an electrical switch having an improved contact construction which prevents galling of the contacts.

Another object of the invention is the provision of an electrical switch having an improved construction which provides uniform restricted area contact at the hinge end, and which seals out the dirt to prevent galling of the contact, and which also seals in the lubricant so as to keep the hinge contact permanently lubricated.

Another object of the invention is the provision of methods for forming contact elements having the characteristics noted above.

Another object of the invention is the provision of an improved electrical switch, as described in the preceding paragraphs, which is simple, reliable in operation, and inexpensive to manufacture and assemble.

In carrying out the invention, the break end of each switch blade is embossed to provide a raised contact portion having a serrated or knurled contact surface, thus providing a multiplicity of lines, ridges or points on the contact surface. The copper switch blades with or without an overlaid silver surface have bodies that can be deformed with relative ease. With this construction, even though the blades are not accurately aligned with the tongues and both are not perfectly flat and true, a uniform and proper contact over the entire contact length and uniform tongue marking is obtained. This is accomplished by reason of the fact that any of the lines, ridges or points which touch the tongue first due to the parts not being true and perfectly aligned, will wear down or cut into the tongue after a few successive opening and closing operations of the switch until all of the ridges, lines, or points finally contact with the tongue.

The hinge ends of the switch blades are also embossed to provide a raised contact portion having concentric circular serrations or ridges. The ridges wear in as the switch operates until all of the ridges contact with the tongue. As soon as the outer ridges contact with the tongue, they form a seal against external dirt or foreign matter getting into the contact, and also act to seal in whatever lubricant is used, thus keeping the contact permanently lubricated.

The novel features that are considered characteristic of the invention are set forth in particular in the appended claims. The invention itself, however, both as to construction and operation, together with additional objects and advantages thereof, will best be understood from the following detailed description of several embodiments thereof when read in conjunction with the accompanying drawings, in which:

Figure 1 is a plan view of an electrical switch

constructed in accordance with the invention;

Fig. 2 is a side elevational view of the switch shown in Fig. 1;

Fig. 3 is an enlarged side elevational view of one of the switch blades showing the inner side of the blade;

Fig. 4 is an enlarged plan view of the switch blade;

Fig. 5 is an enlarged fragmentary cross-sectional view of the raised contact portion at the break end of the switch blade;

Fig. 6 is an enlarged fragmentary side elevational view of a switch blade having a slightly modified raised contact portion;

Fig. 7 is a fragmentary enlarged cross-sectional view of the raised contact construction shown in Fig. 6;

Fig. 8 is an enlarged fragmentary side elevational view of a switch blade having a further modified raised contact portion;

Fig. 9 is a fragmentary plan view of the switch blade shown in Fig. 8; and

Fig. 10 is an enlarged sectional view through the hinge end of the switch.

Referring to the drawings, and particularly to Figs. 1 and 2 thereof, the reference numeral 11 designates a rigid supporting base upon which is mounted a pair of spaced insulating columns 13 for supporting the switch. The insulating columns 13 are preferably formed of vitreous material, such as porcelain or the like, and are secured to the base 11 by means of a plurality of bolts 15.

A pair of switch terminals 17 and 19 are rigidly secured, as by bolts 21, to the metal caps 23 of the insulating columns 13. The terminals 17 and 19 are of conducting material, preferably copper, or a suitable alloy of copper, and are provided with generally rectangular, flat contact tongues 25 and 27, respectively, which project outwardly from the flat bases of the terminals. The contact tongues 25 and 27 may be formed integral with the terminals or may constitute separate elements which are secured to the terminals in any suitable manner, as, for example, by welding. Each of the terminals is also provided with an integral terminal connecting portion 29, which projects beyond the end of the switch and serves for connecting electrical conductors to the switch terminal.

One of the terminals 17 serves as a hinge terminal, and a pair of mechanically connected switch blades 31 are pivoted at one end by means of a through bolt 33 to the contact tongue 25 of this hinge terminal 17. The blades are thus mounted for swinging movement into and out of engagement with the break contact tongue 27 of the break terminal 19.

The switch blades 31 are composed of flat metal bars, preferably of copper, and are mounted to engage the opposite sides of the contact tongues 25 and 27. The two blades are mechanically connected together adjacent their free ends by means of a through bolt 35, and the blades are biased towards each other to engage the contact tongues with a predetermined pressure by means of the spring cup washers 37. The cup washers 37 are mounted on the through bolts 33 and 35 at the hinge and break ends of the switch, and are held in tension against the outer sides of the two blades by means of the heads of the through bolts and by the nuts 39 threaded on the ends of the through bolts.

The break contact tongue 27 is provided with

a recess adjacent its outer end for accommodating the through bolt 35 when the switch is closed, and the outer edges of this break contact tongue 27 are beveled, as indicated in Fig. 1, to facilitate closing of the switch. The beveled edges serve to guide the free ends of the switch blades 31 onto the break tongue 27 and also act as wedges to spread the free ends of the blade during closing of the switch.

10 A latch device is provided for releasably latching the switch blades 31 in closed position. This latch device comprises a latch 41 which is pivotally mounted at 43 on the break terminal 19 beyond the contact tongue 27, and a latch pin 45 carried by the free ends of the blades and extending transversely therebetween. The pivoted latch 41 is biased to latching position by a spring 47, and the nose 49 of the pivoted latch is adapted to extend in the space between the free ends of the blades 31 and to engage the latch pin 45 when the blades are in closed position to releasably lock the blades in this position.

15 An operating eye 51 is pivotally mounted between the free ends of the blades 31 by means of a through bolt 53, and this operating eye has a projecting arm 55 formed integral therewith which is adapted to engage the inclined edge of the nose 49 of the latch 41 when the switch is closed. The operating eye 51 serves as a means for releasing the latch, and for operating the switch blades 31 to open and closed circuit position.

20 When the operating eye 51 is pulled to open the switch, it first operates to force back and release the latch 41 to free the switch blades for opening movement. Further pull on the operating eye pries the blades out of their high pressure engagement with the break tongue 27, and thereafter moves the blades 31 about their pivot axis 33 to open position. A stop pin 57, extending transversely between the blades, is adapted to engage the projecting arm 55 of the operating eye 51 to limit clockwise rotation of the operating eye on its pivot bolt 53, thus permitting the eye to be pushed to effect closing of the switch. The latch pin 45 also serves as a stop to limit counter-clockwise rotation of the operating eye 51 about its pivot axis 53 during opening of the switch.

25 The operating eye and the latch device are preferably of the same general type and construction as fully described and claimed in my copending application for Electrical switches, Serial No. 180,394, filed December 17, 1937, and assigned to the assignee of the present invention.

30 It has been found desirable to restrict the contact area at both the hinge and break ends of the switch to an order substantially that of line or point contacts, or at least to an order considerably less than that of the transversely aligned surfaces. This provides a high contact pressure per unit of contact area, resulting in a very good and efficient electrical joint. This restricted contact area is obtained in one way by providing the switch blade or blades with elongated raised contact portions at the break end and with annular raised contact portions at the hinge end concentric with the pivot axis. The raised contact portions engage the flat surfaces of the contact tongues and thus restrict the contact area.

35 As has previously been pointed out, one very important difficulty that has been experienced with this general type of switch, as well as with

other types, has been in making the contact portions of the blades contact uniformly with the contact tongue. This is necessary to prevent localized points of contact and to obtain uniform abrasion or marking of the contact tongue. It is apparent that to obtain uniform contact and to show uniform abrasion or marking of the contact tongue, the blades and tongues must be perfectly true and perfectly lined up with each other. This is impractical from a manufacturing standpoint. No matter how carefully machined, the edges of the tongues seem to be higher than the central surface thereof. This may be only on the order of a fraction of a thousandth of an inch, but it is enough to produce a localized point of contact and poorly marked contact tongue. This is also true of the ends of the raised portions on the switch blades.

The present invention provides a switch having restricted area contacts which provide uniform contact and uniform markings on the contact tongues, and these results are obtained in a simple and economical manner without requiring any special truing, aligning and machining operations. In accordance with the present invention, the switch blades are provided with raised contact portions of restricted area having a knurled or serrated contact surface forming a multiplicity of ridges, lines or points for engaging the contact tongue. The copper blade contact member, with or without an overlaid silver surface, has a body that can be deformed with relative ease. The size of the ridges, lines or points is such that any of the ridges, lines or points which contact the contact tongue first, due to the contact members not being perfectly true or perfectly lined up with each other, will wear in or iron down after a few operations of the switch until finally all of the raised ridges, lines or points contact with the tongue. This gives uniform and proper contact over the entire contact length and also provides uniform marking of the contact tongue, even though the tongues and blades are not perfectly true and are not perfectly lined up with each other.

Referring to Fig. 3, each of the switch blades 31 is provided adjacent its free end with an elongated raised contact portion 59 having a knurled contact surface 61 of cross-hatch or waffle-iron design forming a multiplicity of relatively sharp projecting points 63 (see Fig. 5).

The raised contact portion 59 and its knurled contact surface 61 is embossed on the blade by pressing the material out of the principal plane of the blade in an embossing die of the desired configuration.

The elongated raised contact portion may be provided with a knurled contact surface consisting of a multiplicity of parallel relatively sharp-edged ridges, as shown in Figs. 6 and 7, instead of the cross-hatch or waffle-iron design shown in Fig. 3. In the modification of the invention shown in Figs. 6 and 7, the switch blades 31 are provided with elongated raised contact portions 65 having a knurled surface 67 forming a multiplicity of parallel relatively sharp-edged ridges 69 for engaging the contact tongue of the switch. The raised contact portion 65 and its knurled surface 67 are embossed on the switch blade by a pressing operation in a suitable embossing die of the desired configuration the same as in the embodiment of the invention shown in Fig. 3. The embossing die in this modification has a surface configuration to provide the elongated raised contact portion 65

and the multiplicity of parallel sharp-edged ridges thereon as shown in Figs. 6 and 7.

A further modification of the invention is shown in Fig. 8. In this modification, the switch blades 31 are provided with two raised contact portions 71 of relatively short length having knurled contact surfaces 73 forming a plurality of relatively sharp-edged ridges similar to the knurled surface shown in Fig. 6. In this modification, the length of the raised contact portions 71 is shorter than the width between the adjacent edges of the contact tongue, the outline of the contact tongue being shown by the dotted lines 75 in Fig. 8. The raised contact portions 71 and their knurled surfaces are embossed on the switch blades 31 in the same manner as previously described in connection with the other embodiments of the invention. The relatively short length of the raised contact portions 71 and their arrangement permit them to engage the more perfectly flat portions of the contact tongue, avoiding the tongue edges.

The relatively sharp edged parallel ridges on the contact portions of the blades are preferably disposed parallel to the direction of motion of the contact portion of the blade as shown in Figs. 6 and 8, so that the ridges run onto and off of the stationary contact tongue in the manner of sled runners, each ridge making its own track on the surface of the contact tongue and always moving over the same track. With this arrangement the ridges will wear down or cut their own grooves or tracks into the contact tongue so as to uniformly engage the tongue throughout their entire length.

In all of the embodiments thus far described, the relatively sharp-edged raised ridges 69, 71 or the relatively sharp contact points 63 of the raised contact portions of the blades are made of such size that any of the ridges or points which engage the contact tongue first to the exclusion of the others, due to the blades and contact tongues not being perfectly true or perfectly aligned, will wear down or cut into the surface of the contact tongue after a relatively few opening and closing operations of the switch until finally all of the ridges or points completely engage the contact tongue. This provides a uniform contact throughout the contact length and also provides uniform marking of the contact members.

Referring to Figs. 3, 4 and 10, the hinge end of each of the switch blades 31 is provided with an annular contact portion 77 which is raised above the surface of the blade to restrict the contact area at the hinge end of the switch. The surface of the raised annular contact portion 77 is knurled or serrated to provide a multiplicity of concentrically arranged ridges 79 for engaging the hinge contact tongue 25. The raised annular contact portions 77 and their concentric ridges 79 are embossed on the blades by pressing the same out of the material of the blade in a suitable embossing die in the same manner as the contact portions at the break end of the blades.

The concentrically arranged ridges 79 on the surface of the raised contact portions 77 have relatively sharp edges and are of a size such that any of these ridges which touch the hinge tongue first to the exclusion of others, due to the blades and tongue not being perfectly true or being perfectly aligned, will wear down in a few opening and closing operations of the switch until finally all of the ridges 79 completely engage the hinge tongue 25. The construction thus provides multiple line restricted area contacts at the hinge

end of the switch with uniform contact over the entire contact area and uniform marking of the hinge tongue.

As soon as the edges of the outer ridges 79 engage the surface of the hinge tongue 25, these ridges serve to effectively seal the contact region against the entrance of dirt or other deleterious material. This prevents galling of the contact, since it prevents any abrasive dirt from entering the contact region. If by chance any abrasive dirt or material should get into the contact region, as for example during assembly of the switch, this abrasive dirt or material will work itself into the recesses between the concentric ridges 79 where it will not cause galling of the contacts. The knurled surface of the raised contact portions at the break ends of the blades also serves to prevent galling of the contacts.

The outer ridges 79 when in engagement with the surface of the hinge tongue 25 also act to seal in whatever lubricant is used for the hinge end of the switch, thus keeping the contact permanently lubricated.

If desired, the contact portions of the switch blades and the contact portions of the tongues may be provided with a silver surface to provide silver-to-silver contact. The silver surface may be added to the contact portions of the switch blades either before or after embossing the raised contact portions on the blades. The copper switch blade, either with or without an overlaid silver surface, has a body which can be deformed with relative ease so that the blades can be easily embossed to provide the raised contact portions disclosed, and also so that the raised ridges or points which first touch the contact tongue will readily wear down in a few operations of the switch to an extent such that finally all of the ridges or contact points will completely engage the contact tongues.

While the raised contact portions with their knurled contact faces have been disclosed as being formed on the switch blades, it is to be understood that these raised contact portions may be provided on the stationary contact tongues instead of on the blades, if desired. Also, the contact portions have been disclosed as being formed on the contact members by an embossing operation in a suitable embossing die. While this is the preferred method of forming the contact portions, it is to be understood that the raised contact portions and their knurled contact surface may be provided on the contact members in various other ways. For example, the sharp edged ridges or projections could be provided by milling the same. The raised contact portions may be formed integral with the blades or as separate elements to be secured to the blades.

The invention thus provides an improved construction having multiple line or point restricted area contacts which provide uniform contact over the entire restricted contact area, and which give uniform marking of the contact tongues or members. The multiple line or point restricted area contacts are provided in a very simple and economical manner, and the uniform contact and contact marking are obtained by the construction without requiring any special truing, aligning or machining operations.

While the invention has been disclosed in accordance with the patent statutes, it is to be understood that various changes in the structural details thereof may be made without

departing from the spirit of the invention. It is desired, therefore, that the language of the appended claims be given the broadest reasonable interpretation permissible in the light of the prior art.

I claim as my invention:

1. In an electrical switch, a pair of relatively movable contact members having the form of flat metal bars, one of said members having a raised contact portion of restricted area provided with a knurled contact surface.
- 10 2. In an electrical switch, a pair of relatively movable contact members having the form of flat metal bars, one of said members having a raised restricted area contact portion provided with a knurled contact surface forming a multiplicity of parallel relatively sharp edged ridges for engaging the other of said members.
- 15 3. In an electrical switch, a contact member, a switch blade movable into and out of engagement with said contact member, said blade being provided with an embossed contact portion having a serrated contact surface for engaging said contact member.
- 20 4. In an electrical switch, a pair of relatively movable contact members having the form of flat metal bars, one of said members being provided with an embossed contact portion having a knurled contact surface forming a multiplicity of parallel relatively sharp edged ridges for engaging the surface of the other member.
- 25 5. In an electrical switch, a pair of flat contact members, means mounting said members in substantially parallel planes for relative movement into and out of engagement, one of said members having a raised restricted area contact portion pressed out of the principal plane of the member, said contact portion being provided with a knurled contact surface for engaging the surface of the other member when the switch is closed.
- 30 6. In an electrical switch, a pair of spaced blade members, a hinge contact, a tongue contact, means pivotally mounting said blade members on said hinge contact for swinging movement into and out of engagement with said tongue contact, spring means pressing said blades towards each other, said blade members being provided with raised contact portions having knurled contact surfaces forming a multiplicity of parallel relatively sharp edged ridges for engaging said contacts to restrict the contact area.
- 35 7. A contact member for an electrical switch, said contact member comprising a flat metal bar provided with a raised contact portion having a multiplicity of relatively sharp edged parallel ridges on its contact face.
- 40 8. In an electrical switch, a pair of flat contact members, means mounting said members in substantially parallel planes for relative movement into mutual engagement, one of said contact members having a raised restricted area contact portion provided with a knurled contact surface of silver for engaging the contact surface of the other member which is also of silver.
- 45 9. In an electrical switch, a pair of flat contact members, means mounting said members in substantially parallel planes for relative movement into mutual engagement, one of said members being provided with a raised contact portion having a knurled surface for engaging the surface of the other member, said raised contact portion being constituted by die pressing the material out of the principal plane of the blade member.
- 50 10 75

10. In an electrical switch, a pair of flat contact members, means mounting said members in substantially parallel planes for relative movement into mutual engagement, one of said members being provided with a raised restricted area contact portion having a multiplicity of closely spaced relatively sharp projections for engaging the surface of the other member, the size of said projections being such that any which contact the other contact member first will wear down in a few operations of said switch until finally all of said projections contact with said other contact member.

11. A switch comprising a hinge contact member, a blade member pivoted thereon, one of said members being provided with an annular raised contact portion concentric with the pivot axis, and having a plurality of concentric relatively sharp-edged ridges thereon for engaging the other of said members.

12. A switch comprising a hinge contact member, a blade member pivoted thereon, one of said members being provided with a contact portion having a plurality of sharp-edged circular ridges concentric with the pivot axis for engaging the surface of the other member, said ridges being of a size such that the ones which first contact the other contact member wear down after a few operations of said switch so that all of said ridges finally completely engage with said other member.

13. A switch comprising a hinge contact member, a blade member pivoted thereon, one of said members being provided with a contact portion having a plurality of projecting ridges concentric with the pivot axis for engaging the other of said members, the outer ridges serving to prevent the entrance of dirt and other material into the contact area.

14. A switch comprising a hinge contact member, a blade member pivoted thereon, one of said members being provided with a contact portion having a plurality of projecting ridges concentric with the pivot axis for engaging the other of said members to prevent the entrance of dirt into the contact area and to seal in a lubricant in the contact area.

15. A switch comprising a hinge contact member, a pair of switch blades pivoted thereon, said blades being provided with raised annular contact portions having a plurality of projecting ridges concentric with the pivot axis for engaging the hinge member, said ridges being of a size such that any ridges which first contact with the hinge member wear down after a few operations of the switch until all of said ridges finally engage the hinge member, the outer ridges serving to seal dirt out of said contact area and to seal a lubricant in said contact area.

16. A switch comprising a hinge contact member, a blade member pivoted thereon, one of said members being provided with an annular raised contact portion concentric with the pivot axis and having a plurality of concentric sharp-edged ridges for engaging the other of said members, said raised contact portion and said ridges being formed by embossing the same from the material of one of said members.

17. In an electrical switch, a contact tongue, a switch blade movable into and out of engagement with said tongue, said blade being provided with

a raised contact portion of a length less than the width of said tongue for engaging the central portion of the side surface of said tongue, said contact portion having a knurled contact surface 5 providing a multiplicity of relatively sharp projections for engaging said tongue.

18. In an electrical switch, a pair of flat contact members, means mounting said members in substantially parallel planes for relative movement into mutual engagement, one of said members being provided with a raised restricted area contact portion having a plurality of relatively sharp-edged parallel ridges on its contact surface for engaging the other of said members, said ridges being disposed parallel to the direction of relative motion of the contact portions of said contact members.

19. In an electrical switch, a pair of flat contact members, means mounting said members in substantially parallel planes for relative movement into mutual engagement, one of said members being provided with a raised restricted area contact portion having a multiplicity of relatively sharp projecting points on its contact surface for engaging the other of said members.

20. In an electrical switch, a pair of flat contact members, means mounting said members for relative movement into mutual engagement, one of said members being provided with a contact portion having a multiplicity of parallel relatively sharp-edged ridges for engaging the surface of the other of said members, said ridges being disposed parallel to the direction of relative motion of the contact portions of said contact members as they move into engagement.

21. An electrical switch comprising a contact member, a cooperating blade member, one of said members having opposed portions for cooperating with opposite side portions of the other member, 40 said cooperating portions of one of said members having raised restricted area contacts to provide high pressure restricted area contacts when the switch is closed, said raised restricted area contact portions having a multiplicity of closely spaced sharp edged projections for engaging the surface of the other member, and operating means for opening and closing the switch having force multiplying means operable to pry the high pressure limited area contacts out of high pressure engagement prior to moving the blade member to open position.

22. In a circuit interrupter, a pair of cooperating contact members, one of said members having a contact surface formed to provide a multiplicity of closely spaced sharp edged projections for engaging the contact surface of the other contact member with the sharp edges pointing substantially normal to the contact surface of said other contact member.

23. A circuit interrupter comprising a stationary contact member, a cooperating movable contact member, said contact members having the form of flat bars mounted in substantially parallel planes, one of said members having a contact portion provided with a multiplicity of closely spaced relatively sharp edged parallel ridges for engaging the surface of the other contact member with the sharp edges pointing substantially normal to the surface of said other contact member.
